UNITED STATES PATENT OFFICE.

WALDEMAR H. SPANIER, OF GRAND HARBOR, NORTH DAKOTA.

FENCE-POST.

1,121,772.

Specification of Letters Patent.

Patented Dec. 22, 1914.

Application filed April 25, 1914. Serial No. 834,504.

To all whom it may concern:

Be it known that I, WALDEMAR H. SPANIER, a citizen of the United States, residing at Grand Harbor, in the county of Ramsey and State of North Dakota, have invented certain new and useful Improvements in Fence-Posts, of which the following is a specification, reference being had to the accompanying drawings.

10 This invention relates to improvements in fence posts, and more particularly to metallic fence posts.

An object of this invention is the provision of a metallic fence post which comprises a rectangular plate of metal, the plate being bent to form a pair of wings, the wings having improved integral anchoring and bracing means at their lower ends.

20 A further object of this invention is the provision of a metallic fence post, which is substantially V-shaped in cross-section, whereby to provide a pair of wings, the post having a plurality of transverse slots formed therein at the juncture of the wings to receive the line wires of the fence.

25 With these and other objects in view, my invention consists in the novel construction, combination, and arrangement of parts, to be hereinafter more fully described, claimed, and illustrated in the accompanying drawing, in which,

30 Figure 1 is a perspective view of my improved fence post, showing the same in a position for use; Fig. 2 is a sectional view on the line 2--2 of Fig. 1; Fig. 3 is an elevational view of the plate forming the fence post, before the same is bent into its angular form; Fig. 4 is an elevational view of the lower end of the plate, forming the modified form of my post and showing the same before it is bent; and Fig. 5 is a vertical section of the form shown in Fig. 4 after the same has been bent.

35 Referring more particularly to the drawing, the numeral 1 designates generally the fence post which is bent at an angle to form a pair of oppositely extending wings 2, the fence post being substantially V-shaped in cross-section. Formed in the post at the juncture of the wings, is a plurality of spaced transversely extending slots 3, the slots receiving the line wires 4, and having inclined lower walls as at 5. The line wires are normally maintained in the inner ends 50 of the slots by reason of the inclination of the lower walls, and to secure the line wires

in the slots, a locking rod 6 is moved downwardly within the angle of the post for engagement with the line wires to maintain the same within the slots. A substantially V-shaped recess is formed in the lower end of each of the wings 2, thereby forming a tapered entering member 7 on the lower end of each wing, and a tapered angular entering member 8 between the entering members 7. The members 7 are offset to provide horizontally extending portions 9, the entering members 7 being offset outwardly so that the horizontal portions provide suitable braces to prevent the post from tilting in either direction with relation to the line wires. Mounted on the upper edges of the wings is a V-shaped cap 10, the cap presenting an enlarged surface to a hammer or other similar tool (not shown) for driving the post into the ground, the cap also preventing mutilation of the upper edges of the wings by the tool.

40 In setting up my improved post for use, a hole is made in the ground, preferably a foot in depth, and the lower end of the post is disposed in the hole and hammered downwardly so that the entering members 7 and the angular entering member 8 are forced into the ground until the horizontally extending portions 9 are engaged with the bottom of the hole. The earth is then packed into the hole so that the horizontally extending portions 9 are engaged by the earth on their upper and lower faces, and thus provide anchoring members which prevent oscillation of the post in either direction of the line wires.

45 It will be readily understood that a fence post of this construction may be readily used at a corner of the fence by merely providing inwardly extending flanges (not shown) on the upper edges of the wings to receive the upper ends of a pair of corner braces (not shown), the line wires engaging against the outer faces of the wings to extend around two sides of the inclosure.

50 In Figs. 4 and 5 of the drawing, I have illustrated a slightly modified form of the post, in which the post 1^a at the juncture of its wings 2^a at the lower end of the post is cut away to provide a rounded extension 11 on one of the wings and a tapered extension or entering member 12 on the other wing. In this form, the post is inserted 55 into a hole in the ground in the same manner as the post illustrated in Fig. 1, until

the horizontally disposed extension 11 engages the bottom of the hole, whereupon the earth is then packed into the hole so that the portion 11 provides an anchoring member which prevents oscillation of the post.

Having thus fully described my invention, what I desire to claim and secure by Letters Patent is:—

10. A fence post comprising a strip bent at an angle to form a pair of oppositely extending wings, the lower end of each wing having an angular recess formed therein to provide a tapered angular entering mem-

ber therebetween, the portions of the strip 15 outwardly of the recesses forming tapered entering members, the last mentioned entering members having their lower ends offset outwardly to provide horizontal portions at the juncture of the members with the body 20 of the strip.

In testimony whereof I hereunto affix my signature in the presence of two witnesses.

WALDEMAR H. SPANIER.
